UNITED STATES PATENT OFFICE.

ERNEST C. BOWERS AND EUGENE COOK, OF KALAMAZOO, MICHIGAN, ASSIGNEES, BY
DIRECT AND MESNE ASSIGNMENTS, TO NATIONAL STANDARD COMPANY, OF NILES,
MICHIGAN, A CORPORATION OF MICHIGAN.

DRILLING-MACHINE.

1,073,322.

Specification of Letters Patent. Patented Sept. 16, 1913.

Application filed October 8, 1912. Serial No. 724,515.

To all whom it may concern:

Be it known that we, ERNEST C. BOWERS and EUGENE COOK, citizens of the United States, residing at Kalamazoo, Michigan, have invented certain new and useful Improvements in Drilling-Machines, of which the following is a specification.

This invention relates to improvements in drilling machines.

10 Our improvements are particularly designed by us for use in railway track drills and we have shown the same embodied in such a structure, although certain features are desirable and readily adapted for other 15 forms of drilling or boring machines.

The main objects of this invention are, first, to provide in a drilling machine an improved feed mechanism whereby the drill may be rapidly advanced to or retracted 20 from the work. Second, to provide an improved drilling machine having these advantages, in which the rapid advancing or retracting of the drill is effected through the main operating crank. Third, to provide 25 a mechanism having these advantages which automatically releases the feed screw under undue stress, thereby relieving the drill.

Further objects, and objects relating to 30 structural details will definitely appear from the detailed description to follow.

We accomplish the objects of our invention by the devices and means described in the following specification.

35 The invention is clearly defined and pointed out in the claims.

A structure which is a preferred embodiment of our invention is clearly illustrated in the accompanying drawing forming a 40 part of this specification, in which—

Figure I is a side elevation of a structure embodying the features of our invention, it being shown in operative relation to a rail, no attempt being made to show the 45 rail in its proper proportions. Fig. II is a detail horizontal section on a line corresponding to line 2—2 of Fig. I. Fig. III is a detail vertical section on a line corresponding to line 3—3 of Fig. II. Fig. 50 IV is a detail view showing the rear end of the tool holder, the feed screw and the rapid feed dog, the feed screw being shown in longitudinal section and the dog in its disengaged position. Fig. V is a detail

section on a line corresponding to line 5—5 of Fig. II, showing the driving cam for the rock shaft 24. Fig. VI is a detail view partially in section on a line corresponding to line 6—6 of Fig. II, showing details of the feed mechanism. Fig. VII is a detail section on a line corresponding to line 7—7 of Fig. VI. Fig. VIII is a detail section on a line corresponding to line 8—8 of Fig. II. Fig. IX is a detail section on a line corresponding to line 9—9 of Fig. I, showing details of a crank.

In the drawing similar reference characters refer to similar parts throughout the several views, and the sectional views are taken looking in the direction of the little arrows at the ends of the section lines.

Referring to the drawing, the frame 1 is provided with a bar-like base 2 disposed toward its rear end. The standard or upright 3 is pivoted to the side members of the frame at 4 to collapse rearwardly upon the frame. The standard or upright is held in its erected position by the jointed braces 5. The rail hooks 6 are pivoted to rearwardly projecting arms on the lower end of the standard 3 at 7 so that when the standard is erected stress is put upon the hooks engaged over the rail, at 8. The hooks are provided with a hand piece 9 at their outer ends. This general structure forming no 85 part of our present invention, is not described with greater detail herein.

The tool holder or spindle 10 is provided with a suitable chuck 11 for the drill 12. The tool holder is supported in a bearing 90 13 on the forward end of the frame 1 and its rear end projects into the longitudinally bored screw 14. The feed screw and drill holder are connected by the swivel 15. The tool holder is provided with an annular 95 groove 16 which is engaged by the screw 17 on the feed screw, thereby securing the parts together.

The feed nut 18 is arranged in a housing 19 provided therefor formed in the cross-piece 28 at the rear end of the frame 1. See Figs. II and III. This housing is open at the bottom so that the nut may be slipped into the housing from the bottom and the feed screw inserted through the housing and 105 nut. The nut 18 receives the thrust of the feed screw.

The feed wheel 20 is arranged in front

of the feed nut and provided with a spline 21 engaging the longitudinal groove 22 in the feed screw. The feed wheel 20 is a double ratchet wheel, it being formed in the structure illustrated, of two ratchet wheels secured together by the rivets 23. The feed wheel is driven through the rock shaft 24 arranged parallel with the tool holder and feed screw, the rock shaft being supported by the bearing pintles 25. The front pintle of the rock shaft is arranged through the cross piece at the front of the frame 1, and the rear pintle being arranged through an arm 26 on the cross piece 27 of the frame 1. The feed wheel is arranged between this cross piece 27 and the cross piece 28. This mounting for the rock shaft permits the frame 1 being made an integral casting.

The rock shaft is provided with an arm 29 having a pivot or stud 30 at its outer end for the outer pawl 31. The arm 29 is provided with a branch 32 having a pivot 33 for the inner pawl 34. The pawls lie side by side, the inner pawl being retained on its pivot by the outer pawl, the outer pawl being retained by the pin 35.

The tool holder or spindle is driven through the beveled gear 36 splined thereto and the coacting gear 37 on the lower end of the shaft 38 mounted in the standard 3. The gear 37 is thrown into mesh with the gear 36 when the standard is erected and out of mesh when the standard is collapsed. The gear 36 is provided with a cam 39 which coacts with the forked arm 40 on the rock shaft 24 to oscillate the rock shaft. The gear 36 is held against axial movement by the finger 41 on the rock shaft which projects at the rear of the gear. Either of the pawls may be thrown into operative position and thus vary the feed. When both of the pawls are in operative position as shown in Fig. II, the feed is, of course, through the inner pawl 34, the outer pawl 31 being merely an idler. It is however, necessary to throw the pawl 34 out of operative position in order to render the pawl 31 operative. The shaft 38 is driven through the crank shaft 42 having a gear 43 thereon meshing with the gear 44 on the upper end of the shaft 38.

The crank shaft 42 is provided with collars 45 having opposed arms 46 thereon slotted at 47 to receive the cranks 48. The cranks 48 are slidably arranged through these slots and are adjustably retained therein by the set screws 49. The collars 45 are permanently secured to the crank shaft by the pins 50. The inner ends of the collars bear against the side members of the upright 3 thereby securing the crank shaft against longitudinal movement. The further advantages of this crank structure are economy of manufacture, the necessity for squaring the ends of the crank shaft and

broaching the crank being overcome, the cranks are adjustable, and in shipping may be reversed so that its hand piece 51 projects inwardly, thus rendering the structure more compact. By providing the collar 70 with opposed arms 46, it may be made comparatively light as the stresses are equally distributed.

To quickly advance the drill to or retract it from the work, we provide a dog or clutch member 52 which is arranged within the feed screw. The rear end of the tool holder 10 is notched at 53 to provide jaws coacting with the clutch dog. This notch is preferably curved as shown, the engaging portion of the clutch member being curved or rounded, the object of which will appear as the description proceeds. The member 52 is provided with a stem or shank 54 having a head 55 at its outer end, the head having a driving tang 56 adapted to coact with a transverse jaw slot 57 in the rear end of the feed screw, the driving tang being adapted to engage when the member 52 is in engagement with the tool holder, it being shown in engagement in Figs. II and III, and out of engagement in Fig. IV. The member 52 is held yieldingly in its engaging position by the coiled spring 58 arranged within the feed screw as shown in Figs. III and IV. The clutch member is held out of its engaging position by turning the driving tang 56 transversely of the jaw slot 57. The head is preferably knurled to better serve as a finger piece. When the clutch member is 90 disengaged and the drill holder is rotated, the feed screw is operated with a step by step movement to advance the drill by means of the feed wheel.

When it is desired to rapidly advance the 105 drill to or retract it from the work, the clutch member is engaged and on the rotation of the spindle or tool holder, the feed screw is rotated at the same speed, thereby securing the rapid feed. In order to prevent injury to the drill as in the case of the drill being driven against the work with the clutch member in engagement, the engaging jaws of the tool holder and the clutch member are rounded so that they disengage under this undue stress, releasing the feed screw and thus stopping the feed. By this simple arrangement we provide means whereby the rapid advancing or retracting of the drill is secured, the same being operated through the main operating crank of the machine. The clutch is quickly and easily engaged or disengaged so that very rapid manipulation is possible.

We have illustrated and described our 125 improvements in detail in the form in which we have embodied the same. We have not attempted to illustrate or describe various modifications which we contemplate as such modifications or variations in struc- 130

tural details will be readily understood by those skilled in the art to which this invention relates, from the disclosure made. We desire, however, to be understood as claiming our improvements specifically in the form illustrated as well as broadly within the scope of the appended claims.

Having thus described our invention, what we claim is new and desire to secure by Letters Patent is:

1. In a drilling machine, the combination of a tool holder; a feed screw therefor having a longitudinal bore therein into which the rear end of the tool holder projects, there being a transverse curved notch in the rear end of said tool holder and a transverse notch in the rear end of said screw; a swivel connection for said tool holder and feed screw; a fixed feed nut for said feed screw; a feed wheel splined upon said feed screw; driving connections for said feed wheel and tool holder, said driving connections being adapted to be disengaged from said feed wheel; a clutch member for securing said feed screw to said tool holder arranged within said feed screw and provided with a rounded tool holder engaging portion at its inner end and with a head at its outer end having a driving tang thereon adapted to engage said notch in the rear end of said screw; and a spring arranged within said feed screw for yieldingly supporting said clutch member in its engaging position, said clutch member being held out of its engaging position by turning the tang thereof transversely of the said notch in the rear end of the screw.

2. In a drilling machine, the combination of a tool holder; a feed screw therefor having a longitudinal bore therein into which the rear end of the tool holder projects, there being a notch in the rear end of said tool holder and a notch in the rear end of said screw; a swivel connection for said tool holder and feed screw; a fixed feed nut for said feed screw; a feed wheel splined upon said feed screw; driving connections for said feed wheel and tool holder, said driving connections being adapted to be disengaged from said feed wheel; and a clutch member for securing said feed screw to said tool holder arranged within said feed screw and provided with a tool holder engaging portion at its inner end and with a driving tang adapted to engage said notch in the rear end of said screw.

3. In a drilling machine, the combination of a tool holder; a feed screw therefor, there being a transverse curved notch in the rear end of said tool holder and a transverse notch in the rear end of said screw; a swivel connection for said tool holder and feed screw; driving means for said feed screw and tool holder, the driving means for the feed screw being adapted to be dis-

engaged; a clutch member for securing said feed screw to said tool holder arranged within said feed screw and provided with a rounded tool holder engaging portion at its inner end with a driving tang at its outer end adapted to engage said notch in the rear end of said screw; and a spring arranged within said feed screw for yieldingly supporting said clutch member in its engaging position, said clutch member being held out of its engaging position by turning the driving tang thereof transversely of the said notch in the rear end of the screw.

4. In a drilling machine, the combination of a tool holder; a feed screw therefor, there being a transverse notch in the rear end of said tool holder and a transverse notch in the rear end of said screw; a swivel connection for said tool and feed screw; driving means for said feed screw and tool holder the driving means for the feed screw being adapted to be disengaged; a clutch member for securing said feed screw to said tool holder arranged within said feed screw and provided with a tool holder engaging portion at its inner end with a driving tang at its outer end adapted to engage said notch in the rear end of the screw.

5. In a drilling machine, the combination of a tool holder; a feed screw therefor; a swivel connection for said tool holder and feed screw; a fixed feed nut for said feed screw; a feed wheel splined upon said feed screw; driving means for said feed wheel and tool holder, said driving means being adapted to be disengaged from said feed wheel; a clutch member for securing said feed screw to said tool holder arranged longitudinally within said feed screw; and a spring for yieldingly supporting said clutch member in its engaging position.

6. In a drilling machine, the combination of a tool holder; a feed screw therefor; a swivel connection for said tool holder and feed screw; driving means for said feed screw and tool holder; a clutch member arranged for longitudinal adjustment within said feed screw, said tool holder and feed screw having jaws adapted to coact with said clutch member.

7. In a drilling machine, the combination of a tool holder; a feed screw therefor; a swivel connection for said tool holder and feed screw; a fixed feed nut for said feed screw; a feed wheel splined upon said feed screw; driving means for said feed wheel and tool holder, said driving means being adapted to be disengaged from said feed wheel; and means for securing said feed screw to said tool holder so that it is rotated therewith.

8. In a drilling machine, the combination of a tool holder; a feed screw therefor; a swivel connection for said tool holder and feed screw; driving means for said feed

screw and tool holder; a clutch member for connecting said feed screw and tool holder to rotate together; and a spring for yieldingly supporting said clutch member in its 5 engaging position whereby it is permitted to disengage under excessive stress.

9. In a drilling machine, the combination of a tool holder; a feed screw therefor; a 10 swivel connection for said tool holder and feed screw; driving means for said screw and tool holder; and disconnectible means for securing said feed screw to said tool holder so that it is driven therewith, all 15 coacting for the purpose specified.

15 10. In a drilling machine, the combination with the frame, of a tool holder; means for driving said tool holder; a feed screw; a double ratchet feed wheel; a pair of coacting pawls; a rock shaft journaled in said 20 frame and driven with said tool holder; and an offset pawl carrying arm on said rock shaft provided with a pivot at its end for the outer pawl and with a branch having a pivot at its end for the inner pawl whereby 25 the pawls are pivotally supported at different distances from the axial center of the rock shaft and have different strokes, the

inner pawl being retained on its pivot by the outer, the outer being retained by a pin.

11. In a drilling machine, the combination 30 with the collapsible frame, of a tool holder on the base portion of the frame, a feed screw, a ratchet feed wheel for said screw, a tool holder gear provided with a cam splined to said tool holder, a driving gear 35 therefor carried by the movable portion of said frame and adapted to swing away from said tool holder gear when the frame is collapsed, a rock shaft journaled in said frame and provided with a forked arm coacting 40 with said cam and with a finger disposed to retain said tool holder gear in position when the driving gear is swung away therefrom, and a tool on said rock shaft coacting with 45 said feed wheel.

In witness whereof, we have hereunto set our hands and seals in the presence of two witnesses.
